Primary Examiner — Darlington Ly*Assistant Examiner* — D. Ryan Tisdale(57) **CLAIM**

I claim the ornamental design for an automotive wheel, as shown and described.

DESCRIPTION

FIG. 1 is a front perspective view of the automotive wheel of my claimed design;

FIG. 2 is a front view of the automotive wheel of FIG. 1; and,

FIG. 3 is a back view of the automotive wheel of FIG. 1. The broken lines shown in FIG. 1-FIG. 3 are for the purpose of illustrating portions of the automotive wheel that form no part of the claimed design.
